TRANSISTORIZED MULTIVIBRATOR MODULATOR WITH STARTING CIRCUIT

Boyd L. Stratton, Woodside, Calif., assignor to Ampex Corporation, Redwood City, Calif., a corporation of California

Filed Nov. 29, 1963, Ser. No. 326,926
2 Claims. (Cl. 332—14)

The present invention relates generally to frequency modulators and more particularly to a wide band frequency modulation device, which incorporates a multivibrator.

The process of modulation in general involves producing a composite waveform, some characteristic of which varies in accordance with the instantaneous value of the input signal wave, called the modulating wave. In frequency modulation or FM, the instantaneous frequency of the signal to be modulated, which is ordinarily referred to as the carrier wave, is caused to depart from its initial frequency by an amount proportional to the instantaneous value of the modulating signal.

Television or other wide band tape recording systems normally employ a frequency modulated system to record the video signal on a magnetic tape. In the frequency modulation system, the modulating signal (i.e., the video or other wide band signal) either directly modulates a multivibrator operating at the carrier frequency or modulates a high frequency oscillator which is then heterodyned to provide the signal to be recorded. The carrier frequency is slightly higher than the maximum frequency of the video or other wide band signal, and the ratio of the change or deviation of the carrier corresponding to the maximum modulating frequency is such that the information transmitted by the frequency modulated signal is effectively contained in the carrier frequency component and the first upper and lower side band components.

The direct modulation system using a freely oscillating multivibrator is simpler than the heterodyne modulation system, but it is subject to certain problems. In this connection, a multivibrator tends to be unstable, and/or nonlinear, when the frequency thereof is varied over a wide range. More important, since the frequency of the multivibrator is just above the highest modulating frequency there is a tendency for the higher frequencies of the modulating signal to feed-through the multivibrator and combine with the frequency modulated signal, thereby causing pattern interference.

Heterodyne type modulators permit partial control of the feed-through of the modulating signal, but are subject to frequency drift, harmonic distortion, and intermodulation effects.

It is an object of the present invention to provide a multivibrator type modulator in which feed-through of the modulating signal into the frequency modulated output is eliminated. Another object of the invention is to provide a multivibrator type modulator having substantially reduced harmonic distortion and intermodulation effects. Another object of the present invention is to provide a multivibrator type modulator having a substantially increased linearity and high frequency response. A further object is the provision of a multivibrator type modulator, which is simple to operate, highly stable and reliable, and economical to manufacture and maintain.

Further objects and advantages of the invention will become apparent by reference to the following description and accompanying drawing, wherein the sole figure is a schematic circuit diagram of a preferred embodiment of a wide band multivibrator type modulator.

Generally, the disclosed modulator includes a free-running multivibrator, the frequency of which is varied in accordance with an input signal. The modulator in-

2

cludes a pair of amplifying means 10a and 10b, each of which has a substantially conducting state of operation and a substantially non-conducting state of operation. The amplifying means 10a and 10b are cross coupled by means 14a and 14b including capacitors 16a and 16b. A pair of constant current sources 18a and 18b are respectively coupled to the junction 20a and 20b of the capacitors and the associated inputs of the amplifying means 10a and 10b to thereby provide a free-running multivibrator 22 which oscillates at a frequency dependent upon the current provided by the sources 18a and 18b. An input or modulating signal is coupled to both current sources 18a and 18b to vary the currents supplied by the sources 18a and 18b in accordance with the modulating signal.

More specifically, in the embodiment of the invention shown in the accompanying drawing, the input or modulating signal, which is a video or other wide band signal, is amplified by a suitable video amplifier 24 which preferably includes pre-emphasizing circuitry for providing pre-emphasis. The output of the video amplifier 24, which is a direct current signal, varying in accordance with the input video signal, is coupled to the free-running multivibrator 22 so as to vary the frequency thereof. In this connection, as more fully explained hereinafter, the frequency of the multivibrator 22 is controlled by varying the charging current supplied to the cross coupling capacitors 16a and 16b in accordance with the output of the video amplifier 24.

The illustrated free-running multivibrator 22 comprises two similar cross-coupled circuits A and B (i.e., the output of each circuit is coupled to the input of the other circuit). For purposes of description, the parts of the left hand circuit A in the drawing (hereinafter referred to as the "left hand circuit") are indicated with the reference numeral and the subscript "a." Corresponding parts in the other circuit B, the right hand circuit in the drawing (hereinafter referred to as the "right hand circuit") are indicated with the same reference numeral and the subscript "b."

Each circuit includes the amplifying means 10a, 10b which in the illustrated embodiment is an n-p-n transistor 26a, 26b coupled in a grounded emitter configuration. Each amplifying transistor 26a, 26b is biased so as to operate either in a substantially non-conducting or a substantially conducting state. In this connection, the emitter 28a, 28b is grounded and the collector 30a, 30b is coupled through a load resistor 32a, 32b and an isolation resistor 34 to a positive voltage source (not shown) at terminal 36. The base 38a, of the amplifying transistor 26a, is coupled to the output of the cross coupling means 14b of the right hand circuit b, while the base 38b of the amplifying transistor 26b is coupled to the output of the cross coupling means 14a of the right hand circuit A.

In the illustrated embodiment, each cross coupling means 14a, 14b includes the capacitor 16a, 16b, one end of which is connected to the base 38b, 38a of the amplifying transistor 26b, 26a of the opposite circuit, and an isolating means 42a, 42b coupled between the collector 30a, 30b of the amplifying transistor 26a, 26b and the other end of the capacitor 16a, 16b. By isolating the output of the amplifying means 10a, 10b from the capacitor 16a, 16b, a faster rise and fall time is provided on the output signal. The illustrated isolating means 42a, 42b is an n-p-n transistor 44a, 44b coupled in a common collector configuration, sometimes called an emitter follower. In this connection, the collector 30a, 30b of the amplifying transistor 26a, 26b is directly connected to the base 46a, 46b of the isolating transistor 44a, 44b, the collector 48a, 48b of the isolating transistor 44a, 44b is connected through the isolating resistor 34 to the positive voltage terminal 36, and the emitter 50a, 50b is coupled through a load resistor 52a, 52b to ground. The other end of the

capacitor 16a, 16b is connected to the junction between the load resistor 52a, 52b and the emitter 50a, 50b.

The frequency of the oscillation of the free-running multivibrator 22 depends upon the time it takes for the base to emitter voltage of the amplifying transistor 26a or 26b, which is in its non-conducting state of operation, to reach its switching voltage. The attainment of this voltage depends on the rate of build-up of charge on the respective cross coupling capacitors 16b and 16a. In order to provide linear operation of the multivibrator 22 over very large swings in deviation, the capacitors 16a and 16b are respectively charged from the constant current sources 18a and 18b.

In the illustrated embodiment, each constant current source 18a, 18b includes a p-n-p transistor 54a, 54b connected in a common base configuration. In this connection, the base 56a, 56b is connected through the isolating resistor 34 to the positive voltage terminal 36, and the collector 58a, 58b is connected to the junction between the capacitor 16a, 16b and the base 38b, 38a of the amplifying transistors 26b, 26a. The currents supplied by the constant current transistors 54a and 54b to the capacitors 16a and 16b, respectively, are controlled by connecting the emitters 60a and 60b through a common balancing and adjusting network 62 to the positive voltage supply.

The balancing and adjusting network 62 includes means a potentiometer 64, or equivalent means, for balancing the rate of build-up of charge or the current to the cross coupling capacitors 16a, 16b, means a potentiometer 66, or equivalent means for balancing the modulation of the current to the capacitors 16a, 16b by the modulating signal, and means 68 for adjusting the center or carrier frequency of the modulator 22. The center frequency adjusting means 68 includes a rheostat connected in series with both of the emitters 60a and 60b of the constant current transistors 54a and 54b, between the emitters 60a and 60b and the positive voltage terminal 36. The adjustment of the means 68 will set the free-running frequency of the multivibrator.

The opposite ends of potentiometer 64 are connected respectively through series resistors 65 and 68 to the emitters 60a and 60b of the constant current transistors 54a and 54b. The tap of potentiometer 64 is connected to one end of the rheostat 68. By properly adjusting the potentiometer 64, the second harmonic component of the instantaneous carrier wave may be substantially reduced and substantially perfect carrier waveform symmetry may be provided. A temperature sensitive resistor 70 is connected in series with the frequency control rheostat 68 in order to reduce the effects of ambient temperature on the carrier frequency.

The potentiometer 66 is provided with a tap which is coupled to the output of the video amplifier 24. The ends of the potentiometer 66 are connected respectively through series resistors 74 and 76 to the emitters 60a and 60b of the constant current transistors 54a and 54b. By adjusting the potentiometer 66 to a position such that the base currents of the amplifying transistors 26a and 26b are equally modulated, distortion and spurious output of the demodulated FM signal are reduced to a minimum.

In the illustrated embodiment, the output of the multivibrator 22 is provided at output terminals 78 and 80 connected respectively to the collector 30b of the right hand amplifying transistor 26b and to ground. Alternatively, the frequency modulated output may be taken from the collectors 30a and 30b of both amplifying transistors 26a and 26b through a transformer (not shown).

In order to ensure starting of the multivibrator 22, a suitable starting circuit 82 is provided in the modulator. In the illustrated starting circuit 82, the signal produced at the collector 30a of the left hand amplifying transistor 26a is employed to show whether or not the multivibrator 22 is oscillating. In the absence of this signal, the starting circuit 82, which is a non-sinusoidal, or relaxation oscilla-

tor, is fired or turned on. The starting circuit 82 is connected so as to cut off the left hand constant current transistor 54a, thereby unbalancing the multivibrator 22. The signal on the collector 30a of left hand amplifying transistor 26a is detected by coupling the same through a capacitor 84 to a load resistor 86. A storage capacitor 90 is charged to the negative peaks of the signal developed across the resistor 86 by coupling the signal developed across the resistor 86 through a diode 91 to the storage capacitor 90. The negative voltage developed across the capacitor 90 is coupled through a resistor 92 to a firing capacitor 94 which is thereby maintained at a voltage below the firing potential of the starting circuit 82. The firing capacitor 94 is charged to the firing potential, in the absence of a signal on the collector, by coupling the positive voltage terminal 36 through the isolating resistor 34 and a resistor 96 to the firing capacitor 94.

The starting circuit 82 includes an unijunction transistor 98, the base 100 of which is coupled to the junction 20 between the firing capacitor 94 and the resistor 96. Base-one 102 of the unijunction transistor 98 is coupled through a resistor 104 to ground. Base-two 106 of the unijunction transistor 98 is coupled through a resistor 108 and the isolating resistor 34 to the positive voltage terminal 36. The firing of the unijunction transistor 98 turns on an n-p-n transistor 110, which is normally biased in a non-conductive state. The transistor 110 is coupled in a common emitter configuration, the base 112 thereof being coupled to the base-one 102 of the unijunction transistor 98, the emitter 114 thereof being grounded, and the collector 116 thereof being coupled through a load resistor 118 and the isolating resistor 34 to the positive voltage terminal 36.

When transistor 110 is turned on, a negative pulse of current appears at its collector 116. This negative pulse is coupled to the emitter 60a of the left hand constant current transistor 54a through a capacitor 120, causing the left hand constant current transistor 54a to be turned off for the duration of the negative pulse. When the constant current transistor 54 is turned off, base current to the right hand amplifying transistor 26b is correspondingly cut off, which momentarily unbalances the multivibrator 22, and causes oscillation of the multivibrator 22 to start. The oscillation of multivibrator 22 results in a signal appearing at the collector 30a of the left hand amplifying transistor 26a which turns off the starting circuit 82.

In normal operation of the illustrated modulator, the maximum modulating frequency approaches the carrier frequency. Hence, the higher modulating frequencies feed through the multivibrator 22 to the output (video feed-through) appearing as amplitude modulation of the FM output signal, unless provision is made for eliminating the same. In the illustrated embodiment, the video feed-through is eliminated by a limiting circuit 122 which eliminates the amplitude modulation at the collectors 30 of the amplifying transistors 26a and 26b and hence the video feed-through. The limiting circuit 122 includes a 50 pair of forward biased diodes 124 and 125, connected respectively to the collectors 30a and 30b of the amplifying transistors 26a and 26b. The other ends of the diodes 124 and 125 are connected to ground through a capacitor 126. Thus, the collector voltage of each of amplifying transistors 26a and 26b appears across the capacitor 126. The maximum voltage appearing across the capacitor 126 is limited by the breakdown of a breakdown or Zener diode 128 connected in parallel with the capacitor 126. Thus, the breakdown voltage of the Zener diode 128 is selected so that any amplitude modulation is eliminated from the output FM signal. It should be understood that the circuit configuration itself minimizes feed-through and the limiting circuit 122 only further perfects the superior circuit feed-through performance.

From the foregoing, it can be seen that a modulator is provided in which video feed-through is eliminated, distribution and intermodulation is reduced, and modulator linearity is increased.

Various changes and modifications may be made in the above described modulator without departing from the spirit or scope of the present invention.

Various features of the invention are set forth in the attached claims.

What is claimed is:

1. A wide band multivibrator type modulator, which is particularly adapted for use in a wide band tape recording system, said modulator comprising two similar circuits, each circuit including an input terminal, an output terminal, a capacitor, one end of which is coupled to said input terminal, a current amplifying means having an input coupled to the other end of said capacitor and having a substantially non-conducting state of operation and a substantially conducting state of operation, a source of constant current coupled to the input of said amplifying means, isolating means coupling the output of said amplifying means to said output terminal, the output terminal of each circuit being coupled to the input terminal of the other circuit to thereby provide a multivibrator oscillating at a frequency dependent upon the currents provided by said sources, a voltage limiting means coupled to the output of each of said current amplifying means for limiting the maximum voltage of said output, starting means having a predetermined threshold at an input thereof above which a signal is produced at an output thereof, said starting means including storage means coupled to said input thereof to maintain a potential thereat below said threshold in the presence of charge stored in said storage means, said starting means including means coupled between one of said amplifying means and said storage means to apply charge thereto in response to periodic time variations in a signal of said one amplifying means, said starting means including means establishing a potential at the input thereof in excess of said threshold in the absence of charge stored in said storage means, said starting means including means coupling the output thereof to one of the constant current sources to reduce the current thereof in response to a signal at the output of said starting means, and means coupled to said

current sources for varying the current supplied by each of said sources in accordance with an input signal.

2. A wide band multivibrator modulator, which is particularly adapted for use in a video tape recorder system, 5 said multivibrator modulator comprising a pair of first transistors each connected in a common emitter configuration and being biased to operate either in a substantially conducting or a substantially non-conducting state, a pair of second transistors each connected in a common collector configuration, the collectors of said first transistors being respectively coupled to the bases of said second transistor, a pair of capacitors cross coupled between the emitters of said second transistors and the bases of said first transistors, a pair of third transistors connected in a common base configuration, the collectors of said third transistors being respectively coupled to the junction between said capacitors and associated bases of said first transistors, means connected to the emitters of said third transistors for biasing the same so that equal base currents 10 flow to said first transistors, means connected to said biasing means for varying the same in accordance with an input signal, a limiting circuit including a pair of forward biased diodes connected respectively to the collectors of said first transistors, a capacitor connecting said diodes 15 to the emitters of said first transistors, and a breakdown diode connected in parallel with said capacitor, and a starting circuit having an input responsive to a variable signal on the collector of one of the first transistors, and an output connected to the emitter of one of said third 20 transistors.
